UNITED STATES PATENT OFFICE.

FRED W. COOLEY, OF MINNEAPOLIS, MINNESOTA.

LOUD-SPEAKING DEVICE FOR SOUND-REPRODUCING MACHINES.

Application filed January 29, 1925. Serial No. 5,463.

This invention relates to a loud speaking device for a sound transmitting or sound reproducing machine, and while the device is capable of many applications, it particularly is designed for use in modern well known radio receiving sets. Such receiving sets usually comprise a casing having a panel at the front thereof, the various parts of the apparatus being disposed in said casing. As is well known, loud speakers are now commonly used with said radio sets. Such a loud speaker should be constructed to properly direct and transmit the sound waves produced so that the reproduced sound will be heard clearly and distinctly.

It is an object of this invention to provide a loud speaker for such a radio receiving set, which loud speaker comprises a tone modifier and is adapted to be secured to the panel of the radio receiving set.

It is a further object of the invention to provide a loud speaking device comprising a tone modifier which is secured to the front panel of the radio receiving apparatus and is disposed between said panel and the sound reproducing device, said parts being supported by said panel.

It is also an object of the invention to provide a loud speaking device for a radio receiving apparatus comprising a tone modifier which is axially aligned with an opening in the front panel of the radio receiving apparatus, a sound reproducing device comprising a diaphragm being secured co-axially with the tone modifier, said parts being supported by said panel.

It is still another object of the invention to provide a tone modifier comprising co-axially arranged spaced tubes, one within the other, with a yielding spacing means therebetween, one of said tubes having a slot formed therein in alignment with the spacing means, together with means for securing said tubes together and clamping said spacing means therebetween.

It is still further an object of the invention to provide a tone modifier comprising spaced co-axially arranged tubes, one within the other, the inner tube having a means secured thereto placing the same under stress, together with means securing the tubes together spaced from said last mentioned means.

These and other objects and advantages of the invention will be fully set forth in the

following description made in connection with the accompanying drawings in which like reference characters refer to the same parts throughout the different views, and in which,

Fig. 1 is a top plan view of the device; Fig. 2 is a central vertical longitudinal section through Fig. 1;

Fig. 3 is a view in end elevation of the device, as seen from the right of Fig. 1; and

Fig. 4 is a horizontal central section of the inner tube with the resilient member used shown therewith.

Referring to the drawings, the device is shown comprising a base plate or member 5 having upstanding therefrom at one end and secured thereto a plate 6. While the base 5 and plate 6 may be constructed in various ways, it is contemplated to have the base 5 form the bottom member of the casing of a radio receiving apparatus and the plate 6 to form the front panel thereof. Small blocks 6^b are shown secured to the top of base 5 and about the rear side of plate 6 by means of which the parts can conveniently be secured together. The plate or panel 6 has a cylindrical opening 6^a formed therein and a casing 7 is provided having a cylindrical passage therethrough of substantially the same size as and co-axially aligned with the opening 6^a. Preferably, a thin washer of yielding or substantially non-elastic material 8 is disposed between the end of casing 7 and panel 6. The casing 7 has a tube 9 of elastic material, such as well seasoned wood, the exterior of which has spaced portions 9^c contacting casing 7 and the remaining cylindrical exterior of which is spaced from the inner wall of casing 7 throughout the greater part of its extent, said tube 9 projecting slightly through the opening 6^a. A smaller tube 10, likewise of elastic material, is disposed in and co-axially with the tube 9 and spaced from the walls thereof. The tube 10 is provided adjacent its end nearest panel 6 with a slot 10^a extending longitudinally thereof at its bottom, the slot having a central circular portion and end portions extending therefrom, as shown in Fig. 4. A spacing member 11 is disposed between tubes 9 and 10 and is aligned with the slot 10^a. While various materials may be used for the spacing member 11, it is preferably made of yielding material.

110

al, and in the embodiment of the invention illustrated, the same is shown as comprising a layer of felt 11^a surrounded with one or more layers of soft yielding material 11^b such 5 as waxed leather. A pair of spaced headed and nutted bolts 12 extend through the member 11, through the ends of the slot 10^a and through spaced holes 9^a formed in tube 9, said tube having a groove or depression 9^b 10 therein extending about and between said holes. Laminated washers 13 of yielding material, such as felt, surround the bolts 12 adjacent both ends thereof, said washers extending across the holes 9^a and the ends 15 of slot 10^a, respectively. Metal washers 14 overlie the washers 13 and are contacted, respectively, by the heads and the nuts on the respective ends of bolts 12. It will be noted 20 that the casing 7 is cut away at its lower end, as indicated at 7^a, to accommodate the washers 13 and 14 and bolts 12. The base member 5 also has an opening 5^a therein for convenient manipulation of the bolts 12. The tube 10, preferably, is placed under 25 stress and for this purpose, has secured thereto a resilient member 15 formed as a strand of resilient wire bent into U-shape, one end of which U-shaped piece is secured to the tube 10 by a headed and nutted bolt 30 16 spaced from an adjacent one of the bolts 12. The member 15, preferably, is enclosed in a layer of soft yielding material 15^a and said member and material are secured against the inner side of tube 10 by the 35 nut 16^a and washer 16^b on bolt 16. The member 15 will be formed normally to extend away from the interior of tube 10 at its end remote from bolt 16 and said member 15 will be placed under stress and 40 brought against the interior of the tube 10 and secured in place by another bolt 17 similar to bolt 16.

The ends of tube 9 and casing 7 remote 45 from panel 6 are flush and abutted by a washer 18 of yielding material, such as comparatively hard rubber and another somewhat thinner washer 19 is spaced from the washer 18, the diaphragm 20 formed of hard elastic material being disposed between washers 18 and 19. The washers 18 and 50 19, as shown, have their openings substantially the same size as the opening through tube 9. The diaphragm 20 has a much smaller opening and has disposed in said 55 opening a headed bushing 21 threaded on its exterior and secured in the front portion 22^a of a telephone receiver 22, a small washer of somewhat resilient material 21^a being disposed between diaphragm 20 and portion 60 22^a. The telephone receiver 22 comprises a rear portion of smaller diameter into which pass the usual conductors 23. A yoke or collar member 24 has an opening therein extending over the reduced rear portion of telephone receiver 22 and engaging the front 65

thereof. The member 24 has holes therethrough at each side of member 22 and bolts or rods 25 extend through said holes and extend at each side of the casing 7 forwardly to and through the panel 6 having heads and washers disposed on the exterior of said panel, said bolts 25 having washers and nuts disposed thereon at the rear of member 24.

Said member is thus drawn toward the panel 6 and the casing 7 with the parts carried thereby is clamped between the telephone receiver 22 and the panel by the member 24 and bolts 25. A cylindrical casing 26 is disposed about the members 18, 19 and 20 and the front part of the transmitter 22 75 and held in place by screws extending into casing 7.

In operation, the device will, as stated, be mounted in the front panel of the radio receiving apparatus, and the sound transmitted will be reproduced in the telephone receiver 22. The diaphragm in the receiver 22 will be actuated and will, in turn, actuate the diaphragm 20 which amplifies the sound. The sound waves then pass through 85 the tubes 9 and 10 and are modified so that a loud, distinct and pleasing tone issues from the front of the device. The tension member for tube 10 is made separate from and spaced from the holding means for the tubes 9 and 10. A yielding spacing member 11 disposed under the slot 10^a is clamped and compressed between the tubes and a portion of this yielding member protrudes into slot 10^a. This assists in keeping the tubes 9 and 10 in perfect axial alignment, which is necessary for the best results. The device is very conveniently arranged for mounting 90 in the standard radio receiving cabinet and it is unnecessary to have any parts mounted upon the cabinet or separate therefrom. The device has been produced after a great deal 95 of experimentation by the inventor and has been demonstrated in actual practice and found to be very successful and efficient. 100

It will, of course, be understood, that various changes may be made in the form, details, arrangement and proportion of the parts without departing from the scope of applicant's invention, which, generally stated, consists in a device capable of accomplishing the objects above stated, such as shown and described and in the novel parts and combinations of parts disclosed and defined in the appended claims. 110

What is claimed is:

1. The combination with the panel of a radio receiving apparatus, of a sound reproducing device including a diaphragm spaced from said panel, a tone modifying device disposed between said panel and said sound reproducing device including a plurality of spaced tubes of elastic material arranged coaxially with said diaphragm, and means extending through said panel to said sound re- 125 130

producing device and securing the latter and said tone modifying device to said panel.

2. A loud speaker for a sound transmitting apparatus having in combination, a panel, a sound reproducing device including a diaphragm spaced from said panel, a cylindrical tone modifying device disposed between said sound reproducing device and said panel and arranged co-axially with said diaphragm, and means secured to said sound reproducing device and said panel for holding all of said parts in position.

3. A loud speaker for a sound dispensing apparatus having in combination, a panel, a sound reproducing device including a diaphragm spaced from said panel, a cylindrical tone modifying device disposed between said reproducing device and said panel, a member embracing said sound reproducing device and extending at each side thereof, and spaced means secured to said member and extending at each side of said tone modifying device and secured to said panel for supporting all of said parts from said panel.

25 4. A loud speaker for a sound transmitting apparatus having in combination, a panel, a telephone receiver spaced from said panel, a tone modifier comprising a plurality of cylindrical members disposed between said receiver and panel, a collar embracing said transmitter, and spaced rods extending from said collar to said panel and securing and clamping said parts to said panel whereby all of said parts are supported from said panel.

35 5. A loud speaker for a sound transmitting apparatus having in combination, a panel having a cylindrical opening therethrough, a casing having a cylindrical passage therethrough extending at one side of said panel with said passage alined with said opening, a tube secured in said casing at the end thereof remote from said panel, a smaller tube secured in said tube co-axially therewith, adjacent the end thereof nearest said panel, said smaller tube having a slot therethrough, yielding spacing means between said tubes and alined with said slot, and securing means connecting said tubes and extending through said spacing means.

40 6. A tone modifying device comprising a tube of elastic material supported adjacent one end, a smaller tube disposed in said tube co-axially therewith and spaced from the walls thereof having a slot through the end thereof remote from the said end of said first mentioned tube, a yielding spacing means be-

tween said tubes alined with said slot, and securing means passing through said tubes and spacing means and clamping said spacing means therebetween, whereby said spacing means protrudes into said slot and assists in maintaining said tubes in axial alinement.

45 7. The structure set forth in claim 6, said securing means comprising spaced bolts, said outer tubes having spaced holes through which said bolts pass, said bolts also passing through said slot in said smaller tube, and members formed of resilient material surrounding said bolts at both ends and spanning said holes and said slot respectively.

70 8. A tone modifying device comprising a tube of elastic material supported adjacent one end, a smaller tube disposed in said tube co-axially therewith and spaced from the walls thereof, spacing means between said tubes adjacent one end thereof, securing means holding said tubes in co-axial relation, and means secured to said inner tube spaced from said securing means for placing said inner tube under stress.

75 9. The structure set forth in claim 8, said last mentioned means comprising a resilient member extending longitudinally along the interior of said inner tube secured at one end and being under stress and secured at its other end.

80 10. A tone modifying device comprising a tube of elastic material supported adjacent one end, a smaller tube disposed in said tube co-axially therewith and spaced from the walls thereof having a slot through the end thereof remote from the said end of said first mentioned tube, said first mentioned tube having a recess on its inner side, a yielding spacing means between said tubes alined with said slot and recess, and securing means passing through said tubes and spacing means and clamping said spacing means therebetween, whereby said spacing means protrudes into said slot and recess and assists in maintaining said tubes in axial alinement.

85 11. A loud speaker for a sound transmitting apparatus having in combination, a panel, a sound reproducing device including a diaphragm spaced from said panel, a cylindrical tone modifying device disposed between said sound reproducing device and said panel and arranged co-axially with said diaphragm, and means for holding said parts in fixed relative position.

In testimony whereof I affix my signature.
FRED W. COOLEY.
